(57) **CLAIM**

The ornamental design for a portable article carrier, as shown and described.

DESCRIPTION

FIG. 1 is a top, front, and left side perspective view of a portable article carrier showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear, and right side perspective view of the portable article carrier of FIG. 1.

FIG. 9 is a top, front, and left side perspective view of a second embodiment of a portable article carrier showing my new design;

FIG. 10 is a front elevation view of the portable article carrier of FIG. 9;

FIG. 11 is a rear elevation view of the portable article carrier of FIG. 9;

FIG. 12 is a left side elevation view of the portable article carrier of FIG. 9;

FIG. 13 is a right side elevation view of the portable article carrier of FIG. 9;

FIG. 14 is a top plan view of the portable article carrier of FIG. 9;

FIG. 15 is a bottom plan view of the portable article carrier of FIG. 9; and,

FIG. 16 is a top, rear, and right side perspective view of the portable article carrier of FIG. 9.

The surface shading illustrated in the drawings is provided merely to highlight the contour of the design; it is not intended to be illustrative of texture or surface ornamentation. The broken lines in FIGS. 10–16 illustrate portions of the portable article carrier that form no part of the claimed design. The broken away and bracketed portions in FIGS. 1–5, 8–13 and 16 indicate that no particular length is claimed for those portions; such lines and any portion of the article between such lines form no part of the claimed design.
